UNITED STATES PATENT OFFICE

2,574,088

FURNACE FOR CONVERTING HYDRO-CARBONS

Henry Ernest Charlton, Ashton-on-Mersey, England, assignor to Petrocarbon Limited, London, England

Application April 5, 1949, Serial No. 85,615
In Great Britain April 12, 1948

3 Claims. (Cl. 23—277)

1

This invention relates to the conversion of hydrocarbons by thermal treatment and includes conversions which take place in the presence or in the absence of a catalyst.

More particularly the invention relates to the carrying out of conversions of hydrocarbons of the kind comprising two consecutive reaction stages of differing heat requirements, the first stage being endothermic and requiring a large heat input, and the second stage being substantially thermo-neutral, or slightly exothermic and requiring no substantial heat input.

Examples of conversions of this kind are the conversions of hydrocarbons which are wholly or mainly non-aromatic substantially completely into olefin-containing gases and aromatic hydrocarbons. Such conversions are referred to in U. K. Patent No. 575,383 and consist essentially of a cracking reaction followed by an aromatisation reaction though the two reactions may overlap to some extent. The cracking reaction requires a large and rapid heat input whilst the aromatisation reaction requires no substantial heat input.

In accordance with the invention a method of, or process for, carrying out conversions of hydrocarbons of the kind referred to above, comprises passing the hydrocarbon starting material in fluid form through a number of reactors which pass through a furnace heated by one or more fluid fuel burners firing into or by hot gases entering that end of the furnace at which the hydrocarbon fluid is introduced into the reactors, the hot gases produced by the burner or burners or introduced into the furnace passing through the furnace in the same direction as the hydrocarbon fluid to leave through a flue at the other or outlet end of the furnace, a cooling blanket of gases being introduced into that part of the furnace between its ends corresponding to the position at which the conversion taking place in the reactors passes from the endothermic stage into the thermo-neutral or slightly exothermic stage.

The firing of the furnace is regulated so as to provide the heat required for the first endothermic stage of the conversion and the temperature and quantity of the cooling gases are such as to reduce the temperature in the succeeding part of the furnace to that required by the second stage of the conversion and to maintain this temperature in the succeeding part of the furnace. All the gases introduced leave the furnace through the flue at the exit end.

The cooling gases may comprise a portion of

2

the flue gases which have left the furnace and have been cooled, as will generally be found necessary, by performing an additional heating operation which may, for example, consist of, or include the vapourising or pre-heating of the fluid fed to the reactor.

The apparatus in accordance with the invention for carrying out conversions of hydrocarbons of the kind referred to, comprises a furnace 10 through which one or more reactors pass, firing means at the inlet end of the furnace providing hot gases which pass through the furnace, an outlet for the gases at the other or outlet end of the furnace and means for introducing a blanket of gases into the furnace between its two ends.

The means for introducing a blanket of gases into the furnace may comprise a duct surrounding the furnace and provided with jets protruding into the furnace. Means may also be provided for circulating part of the flue gases leaving the furnace to this duct. It will generally be found necessary to cool the gases before recirculation to the furnace and this is preferably done by passing them over preheaters or vapourisers for the charging stock mounted in a chamber close to the furnace. Additional cooling, if required, may be carried out by passing the gases over a waste heat boiler.

The reactors used in carrying out the invention preferably comprise an initial portion of relatively high surface to volume ratio designed for the carrying out of the endothermic reaction stage and a following portion of relatively low surface to volume ratio designed for the carrying out of the thermo-neutral or exothermic reaction stage, as described in British Patent No. 575,383. Thus, for example, in applying the invention to the conversion of petroleum fractions into olefin-containing gases and aromatic hydrocarbons the reactor may consist of a tube of 3 inches diameter expanding into a tube of 10 inches diameter.

One method of carrying out the invention as applied to the conversion of hydrocarbons which are wholly or mainly non-aromatic, substantially completely into olefin-containing gases and aromatic hydrocarbons will be described below with reference to the accompanying drawings in which Figure 1 is a perspective view of one construction of apparatus in accordance with the invention and Figure 2 is a cross section through the furnace of the apparatus.

Referring to the drawings, the apparatus comprises a vertical furnace 10 of rectangular cross-

3

section having a number of gas burners 11 firing into the furnace along the major axis of the top of the furnace and an exit flue 12 along the centre of the bottom of the furnace to which the gaseous products of combustion pass through slots 13. A number of tubular reactors 14 (only two of which are shown in Fig. 1) are arranged along each of the longer sides of the furnace 10. Each reactor 14 comprises a relatively narrow tube 15 of 3 inches diameter passing into a relatively wide tube 16 of 10 inches diameter, the narrow part 15 of the reactor being designed for carrying out the cracking stage of the conversion which is endothermic and the wider part 16 of the tube being designed for carrying out the aromatisation stage of the conversion which is thermo-neutral, or slightly exothermic.

Surrounding the furnace 10 at that level at which the narrow part 15 of the reactor 14 enters the wider part 16 is a duct 17 provided with a series of jets 18, 19 protruding into the furnace, a number of jets 18 being arranged along the upper part of the duct 17 and a number of jets 19 being arranged along the lower part of the duct 17 and in staggered relationship to the upper jets 18. Adjacent to the furnace is a chamber 20 containing a number of vapouriser coils 21, each of which is connected to the top of a reactor 14 at one end through a feed pipe 38 and to a common source of liquid hydrocarbon at the other end through a feed pipe 39. The feed pipes 38 connecting the vapourisers 21 to the reactors 14 pass through ducts 40 and 41 along each side of the top of the furnace 10. Each reactor 14 is provided at its lower end with an outlet pipe 42 feeding through a valve 43 into a common off-take pipe 44. Means 45 are provided for quenching the products leaving the reactors 14. The exit flue 12 below the bottom of furnace 10 communicates with a duct 22 which is in communication with chamber 20, the flue gases passing into duct 22 and over the wall 23 into chamber 20. Below chamber 20 is a chamber 24 in which a low pressure steam boiler 25 may be mounted.

On both sides of the chambers 20 and 24 are mounted a series of ducts 26, 27, 28, 29 and 30, the last of which communicates through duct 31 with fan 32 for circulating gases through duct 33 into duct 11. Dampers 34, 35 and 36 are provided for controlling the flow of gases from flue 12. This system of ducts, dampers and fan are provided on both sides of the chambers 20 and 24 though only one system is shown in the drawings.

With the dampers all shut the gases from flue 12 flow up duct 22 over wall 23 through chamber 20, passing over the vapourising coils 21, through chamber 24, passing over the steam boiler 25, and thence out through the duct 37 to the main stack.

By opening damper 35 to the required degree, the desired quantity of the gases leaving chamber 24 may be drawn through ducts 29, 30 and 31 to the fan 32 and passed via duct 33 into duct 11 and distributed through jets 18 and 19 into the furnace. By opening damper 36 to the required degree, the desired quantity of the gases leaving chamber 20 may be made to by-pass chamber 24 and are passed direct to the fan 32 through ducts 28, 30 and 31. By opening damper 34 to the required degree, the desired quantity of the gases coming from flue 12 are caused to bypass the chamber 20 and pass instead through ducts 26, 27 to the chamber 24 and thence, as determined by the position of damper 35, to the fan 32 or duct 37 or to both.

4

By means of the duct and damper system described above accurate control of the quantity and the temperature of the cooling gases distributed into the furnace through the jets 18, 19 is obtained.

The furnace may be fired by oil burners in place of the gas burners referred to above.

The vapour phase conversion at 650 to 750° C. of a non-aromatic petroleum naphtha or kerosene into olefin-containing gases and aromatic hydrocarbons, is carried out in the apparatus described above in the following manner. The charging stock is fed from a liquid container through the feed pipes 39 to the vapourisers 20, in which it is vapourised and superheated and then fed through the feed pipes 38 into the reactors 14, which may be packed with the metallic hydrogenation and dehydrogenation catalyst referred to in British Patent No. 552,216 or with bodies formed of a vitreous ceramic, refractory material such as hard porcelain as described in patent application No. 85,726 filed in the United States on April 5, 1949.

The charging stock is passed through the reactors at a pressure up to about 5, and preferably between 1 and 3, atmospheres gauge pressure and with a space velocity between 0.05 and 0.6 and preferably between 0.2 and 0.6, litres (as liquid) of charging stock per hour per litre of reactor volume.

The products leaving the reactors 14 pass, after quenching by means 45, through the outlet pipes 42 into the off-take pipe 44.

The furnace is fired by the gas burners 11 arranged along the top to give a temperature of about 800 to 900° C. at the top end of the furnace, this temperature gradually falling to about 750 to 800° C. just above the level of the duct. The top parts of the reactors are heated mainly by radiation from the gas flames.

A cooling blanket of gases at a temperature of 300 to 400° C. is introduced from the duct 17 into the furnace through the jets 18, 19 so as to reduce the furnace temperature to about 700° C. and this temperature is maintained down to the bottom of the furnace, the waste gases passing through the slots 13 into the flue 12 and thence are partly passed to the stack and are partly recirculated to the duct 17, after first passing through one or the other or both of chambers 20 and 24.

Though the apparatus has been described with reference to straight tubular reactors, it may be used with other forms of reactors, for example, both the first and second parts of each reactor may consist of coils but it is essential that the first part should be located in the earlier part of the furnace from the firing point to the level of the duct and the second part of the reactor should be located in the succeeding part of the furnace from the duct level to the exit flue.

I claim:

1. An apparatus for converting non-aromatic hydrocarbons into olefin-containing gases and aromatic hydrocarbons which comprises a single chamber furnace, a plurality of straight tubular reactors extending from one end to a second end of said furnace, each of said reactors comprising a straight integral tube including a first portion of relatively small diameter extending from said first end of said furnace to a point of juncture with a second portion of relatively large diameter extending from said point of juncture to said second end of said furnace, said first portion constituting a cracking zone and said second portion

an aromatization zone, means to feed said hydrocarbons to said first portion of said tubes adjacent the first end of said furnace, means to remove products from said second portion of said tubes adjacent the second end of said furnace, means to supply hot gases positioned within said furnace adjacent the first end thereof, exhaust means for said gases communicating with the interior of said furnace adjacent said second end thereof, and means for introducing cooling gases communicating with the interior of said furnace intermediate the ends thereof and adjacent said point of juncture of said tube portions so that said hydrocarbons are heated to a relatively high temperature and supplied with sufficient heat to maintain an endothermic cracking reaction in said cracking zone and are only supplied with sufficient heat to maintain stable temperature conditions in said aromatization zone.

2. An apparatus for the conversion of non-aromatic hydrocarbons into olefin-containing gases and aromatic hydrocarbons which comprises a furnace having a relatively unobstructed firing chamber of substantially rectangular cross-section, a number of burners arranged along the major axis at one end of said chamber, a flue outlet at the other end of said chamber, a plurality of straight tubular reactor tubes arranged along the side walls of the chamber on each side of the burners and extending from the one end to the other end of the chamber, each of said reactors comprising a first portion of relatively small cross-section commencing at the said one end of the chamber and merging into a following portion of relatively large cross-section ending at the

20

30

35

said other end of the chamber, means for introducing cooling gases into the interior of the chamber at about a plane passing through the points of merger of the said initial portions and said following portions of the reactors, means to feed said non-aromatic hydrocarbons to said reactor tubes adjacent the one end thereof and means to remove products adjacent the other end thereof so that the hydrocarbons passing through the said reactor tubes flow in concurrent relation to the gases produced by said burners.

3. The apparatus of claim 1 wherein the means for introducing cooling gases comprises a duct positioned about the furnace intermediate the ends thereof and provided with a plurality of staggered jets communicating with the interior of the furnace.
